UNITED STATES PATENT OFFICE.

HENRY A. CHURCH, OF PROVIDENCE, RHODE ISLAND.

CHAIN-BRACELET.

SPECIFICATION forming part of Letters Patent No. 298,418, dated February 12, 1884.

Application filed July 13, 1883. (No model.)

To all whom it may concern:

Be it known that I, HENRY A. CHURCH, of the city and county of Providence, State of Rhode Island, have invented a new and useful Improvement in Chain-Bracelets; and I hereby declare the following to be a full, clear, and exact description of the same, reference being had to the accompanying drawings, forming a part of this specification.

10 In chain-bracelets one end of the chain has been heretofore secured to the slide or ornament and the other passed through the slide, so that the bracelet could be made large enough to pass over the hand, and then be contracted to 15 drawing one end through the slide, so as to make the bracelet fit the arm. Band and other bracelets have been long before my invention provided with a latch to secure the same together. In the first class of bracelets the end extending 20 beyond the slide or ornament had to be longer than was consistent with good taste, and for persons having large hands and small wrists this pendent end became so long that it was very objectionable to the wearer. In 25 the second class of bracelets the bracelet must be of a fixed size, and cannot be securely worn except at the place and on the arm for which it is particularly made.

The object of this invention is to so construct 30 chain or band bracelets that, while the same can be adjusted on the small part of the wrist over the gloves back of the small part of the wrist, or to arms differing in circumference, they can be readily secured without passing 35 them over the hand.

The invention consists in constructing a 40 bracelet so that one end of the bracelet is secured to the slide by a latch and the other in the slide by friction, as will be more fully set forth hereinafter.

Figure 1 is a view of my improved bracelet. Fig. 2 is an enlarged view, showing the connection of the band with the slide or ornament. Fig. 3 is a view of the end provided with a 45 latch. Fig. 4 is an end view of the slide.

A designates one end portion of a bracelet, and a is a spring-catch, which is secured to or formed upon this end of the bracelet. As shown in the drawings, this catch is formed 50 of a V-shaped spring-plate, one end of which is formed upon or attached to the end of the

bracelet, while the opposite end of the catch is formed with a narrowed portion or tongue. I do not, however, propose to confine myself exclusively to this precise form of catch, as my 55 invention contemplates any form of catch which is held in separable connection with the ornament merely by virtue of its own resilience. The opposite end portion B of the bracelet may be provided with the fringe or 60 other pendant b.

C designates the slide or ornament, which has a friction-stop, e, of cork or other suitable material. The lower portion of the slide C is divided horizontally into two compartments, 65 the upper one of which is open at both ends, and is designed to receive the end B of the bracelet, while the lower compartment, d, which constitutes the catch-socket, is open at one end only. As shown in the drawings, the 70 lower part of the open end of the socket d is formed with a depression or notch to receive the tongue of the catch a, while the raised sides of said notch are engaged on their inner sides by the shoulders at the base of the catch-tongue. It is to be understood, however, that 75 the form of the socket-opening may be varied to suit desired modifications in the form of the catch.

It will be seen that by this novel and peculiar construction the band or chain can be passed around the arm and the end A, secured by the catch a; that then the end B can be drawn through the slide, so as to make the bracelet fit the arm, whether over a glove or 80 sleeve, or the bare arm, without materially extending the loose end or pendant, which therefore can be made of such size that under all 85 usual conditions the bracelet will present a natural and agreeable appearance. As only 90 a moderate adjustment is thus required, the band or chain will not require to be as long as when it has to be drawn over the hand, and the cost is reduced by the saving in the length of the chain or band, as well as a better 95 appearance secured.

Having thus described my invention, I claim as new and desire to secure by Letters Patent—

1. In a bracelet, the combination, with a band carrying a spring-catch at one end, of an 100 ornament arranged to hold one end of the band by frictional contact and to hold the other end

of said band by virtue of the resilient action of the said catch, substantially as described.

2. The combination, with the slide C, provided with the friction-stop e and catch-socket 5 d, of the band or chain provided with the catch a, the whole constructed to secure the bracelet and adjust the same, as described.

3. As a new article of manufacture, a band-bracelet provided with an ornament contain-

ing a friction-stop for adjusting the size of the 10 bracelet, and a socket arranged to receive a spring-catch secured to the end of the band, as described.

HENRY A. CHURCH.
